UNITED STATES PATENT OFFICE.

CHRIST HERMINGHUYSEN, OF VAN WERT, OHIO.

RAILWAY-TIE.

1,346,651.

Specification of Letters Patent. Patented July 13, 1920.

Application filed May 13, 1920. Serial No. 380,997.

To all whom it may concern:

Be it known that I, CHRIST HERMINGHUYSEN, a citizen of the United States, residing at Van Wert, in the county of Van Wert 5 and State of Ohio, have invented certain new and useful Improvements in Railway-Ties, of which the following is a specification.

The invention relates to a railway tie, and 10 more particularly to the class of metallic tie for use with railway track constructions.

The primary object of the invention is the provision of a railway tie of this character, wherein the same includes flexibly connected 15 sections, in which are adapted to be seated the rails of a track, the latter being fastened in place upon the sections so that the tie when in use will not become damaged or broken, due to variance of loads passing over 20 the track and also climatic changes, the tie being permitted to yield when subjected to unevenness of a load and in the expansion and contraction of the rails or the body of said tie, thereby assuring longevity in the 25 use of the same.

Another object of the invention is the provision of a tie of this character wherein the rails of the track can be conveniently fastened in place thereon, and held against 30 sliding action, yet the said rails can move up or down when subjected to variable loads without the possibility of the rails becoming loose from the tie and in this manner compensate for expansion and contraction due to 35 climatic changes of both the tie and rails of the track.

A further object of the invention is the provision of a railway tie of this character, wherein the construction thereof is novel in 40 form so that said tie possesses simplicity, strength, durability, and may be manufactured and installed at a minimum expense.

With these and other objects in view, the invention consists in the features of construction, combination and arrangement of parts as will be hereinafter fully described, illustrated in the accompanying drawing and pointed out in the claims hereunto appended.

50 In the accompanying drawing:

Figure 1 is a top plan view of a railway tie constructed in accordance with the invention showing applied thereto the rails of a track.

55 Fig. 2 is a side elevation of the tie showing the track rails in vertical section.

Fig. 3 is an end elevation of the tie.

Fig. 4 is a vertical longitudinal sectional view through the tie.

Fig. 5 is a sectional view on the line 5—5 60 of Fig. 1.

Fig. 6 is a fragmentary sectional view on the line 6—6 of Fig. 2.

Similar reference characters indicate corresponding parts throughout the several 65 views in the drawing.

Referring to the drawing in detail:

The railway tie comprises separable body sections, A and B respectively, made from metal, each including spaced vertical webs 70 10 of the required width and depth, with which are integrally formed the top and bottom portions 11 and 12 respectively, said bottom portion being considerably wider than the top portion and constitutes a base 75 or tread for the tie.

Each section A and B of the tie has formed in the top portion 11 transversely of the webs 10, a rail engaging seat 13, which is slightly extended beyond the outer faces 80 of the webs 10 and in these seats on both sections are adapted to be placed the rails 14 of a track so that the latter will be supported by the tie.

The section B at the end thereof, adjacent 85 to the section A has integrally formed with the webs 10 intermediate and outer tongues or extensions 15 and 16 respectively, the outer extensions being adapted to overlap the section A at the outer sides of the webs 90 10 thereof, while the intermediate extension 15 is adapted to be inserted between said webs 10 of the section A to seat therebetween, while removably engaged transversely through said extensions 15 and 16, 95 and the said webs 10 of the section A is pivot fastener 17, preferably in the form of a bolt carrying a removable nut so that through the medium of said fastener the sections A and B will be flexibly connected together whereby the load upon one of the sections will not affect the other section and both sections are free for vertical movement independently of each other.

100 Formed on the top portion 11 of each section A and B to project laterally therefrom at opposite sides of the rail seat 13 are ears 18 in which are detachably engaged fasteners 19, carrying cleats 20, for securing the base flange of the rail 14 in the seat 13 and 110 to the section of the tie.

It will be apparent that the rails 14 can

be readily removed from the seats 13 in the sections A and B by detaching the fasteners 19 and the cleats 20 carried thereby when the occasion requires.

5 It is obvious that variable loads upon the track and any unevenness in the loads will cause the sections A and B to yield thereunder and thus the tie in its unity will be prevented from becoming broken or damaged. Furthermore, the construction and arrangement of the tie permits requisite compensation for expansion and contraction thereof and the rails of the track due to climatic changes so that such expansion and contraction will not in any way damage the ties in the use thereof.

10 The rails of the track when fastened upon the tie will be prevented from spreading and a firm and substantial bearing for said rails is had in the use of the tie.

15 The sections A and B of the tie can be readily separated from each other, should it be desired when necessary to make repairs to the track bed or for any other purpose.

20 25 What is claimed is:

1. A railway tie of the character described, comprising a pair of sections, each formed with spaced vertical webs having integral top and bottom portions, said top por-

tion being formed with a rail seat transversely thereof, extensions on the webs of one section and pivotally engaged with the webs of the other section for flexibly connecting the sections together, and means carried by the top portions of the sections for the fastening of rails in the seats.

2. A railway tie of the character described, comprising a pair of sections flexibly connected to each other, each section including spaced vertical webs and top and bottom portions integral therewith, the top portions being formed with rail seats, ears projecting laterally from the top portion on opposite sides of the seats, and rail fastening devices carried by the ears for securing rails within the seat, extensions formed on the webs of one section and engaged between and overlapping the webs of the other section, and a fastener, passed transversely through the extensions and the webs adjacent thereto of said other sections for pivotally connecting both sections together.

30 35 40 45 50 In testimony whereof I affix my signature hereto.

CHRIST X HERMINGHUYSEN.
